UNITED STATES PATENT OFFICE

162,663

AIR CIRCULATOR UNIT

Jacob W. Kisling, St. Louis County, Mo.

Application November 21, 1949, Serial No. 6,179

Term of patent 14 years

(Cl. D26—5)

To all whom it may concern:

Be it known that I, Jacob W. Kisling, a citizen of the United States, residing in the county of St. Louis and State of Missouri, have invented a new, original, and ornamental Design for an Air Circulator Unit, of which the following is a specification, reference being had to the accompanying drawing, forming a part thereof.

In the drawing:

Fig. 1 is a top plan view of an air circulator unit, showing my new design;

Fig. 2 is a side elevational view, the opposite side being identical to the side shown;

Fig. 3 is a perspective view thereof, and

Fig. 4 is a fragmentary sectional view taken along line 4—4 of Fig. 2.

I claim:

The ornamental design for an air circulator unit, substantially as shown.

JACOB W. KISLING.
